UNITED STATES PATENT OFFICE.

MARTIN WOLF, OF NEW YORK, N. Y.

IMPROVEMENT IN TAKE-UPS FOR NARROW-WARE LOOMS.

Specification forming part of Letters Patent No. **58,708**, dated October 9, 1866.

To all whom it may concern:

Be it known that I, MARTIN WOLF, of New York, in the county and State of New York, have invented a new and useful Improvement in Looms; and I do hereby declare that the following is a full, clear, and exact description of the construction and operation of the same, reference being had to the annexed drawings, making a part of this specification, in which—

Figure I is a perpendicular section, Fig. II a front view, and Fig. III a top view, of my improvement.

My improvement relates, particularly, to looms for weaving ribbons, bands, or trimmings, and is for the purpose of regulating the exact amount of the finished work to be taken up, dependent on the thickness of the woof or weft.

In looms as at present constructed the band or woven article, after passing over a roller, A, near the breast-beam of the loom, passes directly to the roller B, operated by suitable gearing, so as to take up the exact amount finished by each throw of the shuttle.

Any irregularity in the thickness of the woof or weft, particularly when the article is woven very tight, will, by the arrangement as at present in use, be very perceptible, as the amount taken up by the roller B is, after once regulated, always the same. To regulate this difficulty resulting from the irregularity of the woof or weft forms the nature of my improvement, which consists of a sliding block, C, arranged between two frames, D D, fastened together by the bars E E, and attached to any convenient part of the frame of the loom. Near the upper end of this sliding block C a roller, F, turning freely on its centers, is arranged, and a roller, G, likewise turning freely around, is arranged near the upper ends of the frames D D.

To the lower part of the block C a pulley, H, is attached, and on the lower part of the frames D D a pulley or roller, K, is arranged.

The ribbon, band, or other material, after having passed over the roller A, is passed below the roller F in the sliding block C, then over the roller G in the fixed frames D D, and then to the take-up roller B.

A cord, L, is fastened to the bottom of the machine, or to the floor of the room, passes then over the pulley H in the lower part of the sliding block C, around the stationary roller or pulley K, then over a pulley, P, fixed to any convenient part of the loom, and has a weight, W, attached to its end.

Instead of attaching the weight W to the end of the cord L, and operating through said cord upon the sliding block C, said weight may be attached directly to the bottom of the sliding block C. By this arrangement of a movable roller between the roller A and roller B any irregularity in the thickness of the woof or weft will be easily regulated without any further attention of the operator, and greater regularity and evenness in the texture of the material woven will be obtained.

By regulating the weight at the end of the cord L, or at the bottom of the sliding block C, the tightness of the texture woven may be easily regulated without changing the motion of the roller B.

What I claim as my invention, and desire to secure by Letters Patent, is—

The arrangement of a movable roller, F, attached to a sliding block, C, and operated or acted upon by a weight, in combination with a stationary roller, G, when applied to the woven material at any place between the breast-beam roller A and the take-up roller B, in the manner and for the purpose substantially as set forth and described.

MARTIN WOLF.
